OTTO H. LANDVATTER, OF DURLACH, GERMANY, ASSIGNOR TO BADISCHE MASCHINEN-FABRIK & EISENGIESSEREI VORMALS G. SEBOLD UND SEBOLD & NEFF, OF DURLACH, GERMANY.

CONVEYING DEVICE FOR MATCH-MACHINES.

1,004,178.

Specification of Letters Patent. Patented Sept. 26, 1911.

Application filed June 27, 1910. Serial No. 569,016.

To all whom it may concern:

Be it known that I, Otto H. LANDVATTER, a citizen of the Confederation of Switzerland, residing at Durlach, in the Empire of Germany, have invented a new and useful Conveying Device for Match-Machines, of which the following is a specification.

My invention relates to improvements in match machines and analogous apparatus, and has especial reference to the mechanism for conveying the completed matches from the dipping devices to the boxing devices.

The principal object of my invention is to provide an improved form of conveyer which will enable the machine to be operated at maximum capacity with minimum risk of damage or delay.

A further object of my invention is to dispense with the employment of chains as the conveying means, and to provide a conveyer which is simple and durable in construction and is free from the defects commonly known to inhere in chain conveyers.

The invention consists of the novel structural features and combinations of features hereinafter more fully described and particularly defined by the appended claims.

I will now proceed to describe my invention with reference to the accompanying drawings, in which—

Figures 1 and 1^a are elevations of the conveying device, parts being shown in section, Fig. 2 is a vertical cross section through the line A—A in Fig. 1, seen in the direction of the arrows, Fig. 3 is a similar section through the line B—B in Fig. 1, seen in the direction of the arrows, Fig. 4 is a vertical cross section on an enlarged scale through the line C—C in Fig. 1, seen in the direction of the arrows, and Fig. 5 is a vertical longitudinal section on an enlarged scale through the left end of the upper trough in Fig. 1 and shows one long rectangular carrier for the most part in elevation.

Similar characters of reference refer to similar parts throughout the several views.

Of the frame of the complete match machine only the lower parts of two standards 1, 2 of the dipping device, a part of the base 5 (a rolled U-beam) for supporting them, two legs 3 and 4 and the table 6 of the match boxing device, and separate portions of sundry brackets 7, 8, 9 are shown. In the bracket 7 and in an eye 14 made in one with the table 6 a horizontal shaft 15

is mounted to turn, which has keyed upon it at the ends two rotary transfer devices D, D. On the brackets 7, 8 and 9 and on the inner end of a suitable support 20 placed on the table 6 a trough 21 (see Fig. 2) is fastened. Two plates 22 and 23 secured on both sides of the support 20 form the continuations of the side walls of the trough 21. A plurality of long rectangular carriers E, E is employed, which are made exactly alike. Each carrier E is in Fig. 5 shown to have four parallel transversely disposed receptacles I, II, III, IV for matches 24, 24. In Fig. 5 a part of the rear wall of the trough 21 is broken away, in order to better show the outlines of the carrier E. The receptacles I, II, III, IV are open on both sides and are each adapted to contain a match box filling and are widened upward, as is clearly shown in Fig. 5, for receiving and pressing together the matches. Each carrier E is provided on the underside at the ends with two opposite notches 25, 25 and on the sides with parallel grooves 26, 26 (Fig. 4). The trough 21 mentioned above serves for guiding the carriers E, E, as can be seen from Fig. 2. The cross section of either rotary transfer device D on the line C—C in Fig. 1 is shown at Fig. 4 and it will be seen, that the rotary transfer device D comprises a long nave 16, an outer system of 6 arms 17, an inner system of 6 arms 18 and six pairs of horizontal opposite guides 19, 19, all these parts being cast in one piece. The guides 19, 19 are adapted to engage in the grooves 26, 26 of any carrier E for holding the latter during the rotation of the rotary transfer device D. On suitable parts of the frame, such as 7, 28, two parallel opposite angle-irons 27, 27 (see Figs. 2 and 3) are fastened, which are connected together by a horizontal metal strip 29 and serve for guiding the carriers E, E. A rail 30 suspended from the two angle-irons 27, 27 by means of strips 31, 31 (Fig. 2) and bows 32, 10, 13 (Fig. 3) and covered with a wooden race 33 serves for supporting the carriers E, E.

A shaft 34 parallel to the one 15 mentioned above is mounted to turn in suitable bearings in the frame and is arranged to be driven from the machine in any known manner. It carries two drums 35, 36 with opposite cam grooves 37, 38, two cam disks 39, 41 and two loose collars with set-screws 40, 42. Two brackets 43, 44 fastened on the

base 5 carry two pins 45, 46 respectively, on which two levers 47, 48 are mounted to rock. The lever 47 carries a pin 49 with a roller 50, which latter engages in the cam groove 57 of the drum 35. In suitable recesses of the brackets 7, 8 and 9 (Fig. 2) a long square bar 51 is guided, which is provided with a projection 52, that is pivotally connected with the upper end of the lever 47 by means of a longitudinally adjustable link 53. The other lever 48 carries a pin 54 with a roller 55, which latter engages in the cam groove 38 of the drum 36. In suitable bows 11, 12 (Fig. 2) fastened on the metal strip 29 another long square bar 56 is guided, which is provided with a projection 57, that is pivotally connected with the upper end of the lever 48 by an adjustable link 58. The cam groove 37 of the drum 35 and the ratio of the lever 47 are so proportioned as to give the bar 51 a stroke which is exactly like the length of each carrier E. The same is the case with the stroke of the lower bar 56. The upper bar 51 is near its left end in Figs. 1 and 5 provided with a spring-pressed pawl 59 within a slot 60 of the bar. The pawl 59 is preferably provided with a rear arm 61 adapted to normally bear against a stop 62, so as to prevent the pawl 59 from turning farther upward. The pawl 59 is adapted to engage in the right notch 25 (Fig. 5) of the upper carrier E in the left rotary transfer device D in Fig. 1 at the moment that the bar 51 is brought into its extreme left position in Fig. 1. The lower bar 56 is near its right end in Fig. 1 provided with a spring-pressed pawl, which is similar to 59, only that it is inverted and is adapted to engage in the left notch 25 of the lower carrier E in the right rotary transfer device D in Fig. 1 at the moment that the bar 56 is brought into its extreme right position. The spaces beneath the guides 19, 19 as shown for the outer arms 17, 17 at Fig. 4 are made deeper for the inner arms 18, 18, as is clearly shown at Fig. 1. Thereby the left end of the upper bar 51 is permitted to move forward to the left in Fig. 1 till a point near the outer arms 17, 17, so that its spring-pressed pawl 59 can engage in the notch 25 as explained above. In a similar manner the right end of the lower bar 56 is permitted to move forward to the right in Fig. 1 till a point near the outer arms 17, 17. Evidently the bottom of the trough 21 requires to be slotted at the left end in Fig. 1 for permitting the pawl 59 to freely move during the reciprocating motion of the bar 51 and for a similar reason the metal strip 29 requires to be slotted at the right end in Fig. 1.

A ratchet wheel 63 is keyed upon the shaft 15, while a lever 64 is loose on this shaft and carries a pawl 65 which engages the teeth of the ratchet wheel 63. The lever

64 is pivotally connected with a rod 66, the lower end of which is forked and is guided on the shaft 34 between the cam disk 41 and the loose collar 42. The rod 66 carries a roller 67 which engages in the cam groove 70 of the disk 41. This cam groove is adapted to reciprocate the rod 66 once on every revolution of the shaft 34, and as the ratchet wheel 63 has six teeth, it will be understood, that either rotary transfer device D is 75 turned through an angle of 60° on every revolution of the shaft 34 in the direction of the arrow 68 in Fig. 4.

The trough 21 is made so long that it will contain an even number of the carriers E, E, 80 so that the carrier E on one rotary transfer device D in line with those in the trough will be supported for its whole length by the said rotary transfer device and all the carriers E E in the whole series will be in contact with one another, so that no play is left between them. The same is the case with the lower series of carriers E E, the two angle-irons 27, 27 and the metal strip 29 having the same length as the trough 21. 90

On the two standards 1 and 2 two opposite bent guides 69 and 70 (see Fig. 2) are fastened for guiding suitable match carriers 71, 71 of the dipping device. I do not show the manner, in which the carriers 71, 71 are 95 intermittently fed forward in the direction of the arrow 72 as it is immaterial to my invention. Each carrier 71 is adapted to carry in its holes a plurality of splints 24, 24 for the dipping operation, and after the 100 dipping into the viscous igniting material the splints now turned into matches are in any known manner dried before they arrive at the conveying device. It depends upon the construction of the respective complete 105 match machine, whether the splints 24, 24 are uniformly distributed over the whole length of the carriers 71, 71, or whether they are disposed in groups as shown at Fig. 1.

On the trough 21 a frame 73 is fastened or 110 held, as the case may be, which frame is provided with dividers 74, 74 and hoppers 75, 75 adapted to collect the matches 24, 24 ejected from the carriers 71, 71 in the following manner. A shaft 76 (Fig. 2) rocking in the standards 1, 2 carries two arms 77, which are connected together by a horizontal rod 78. Several levers 79 are pivotally connected with the rod 78 and are adapted to slide on a shaft 80 forming a part of the 115 machine. At the free ends the levers 79 carry a bar 81 parallel to the carriers 71, 71 and provided with ejectors 82. The shaft 76 is in any known manner actuated by the machine, so that the ejectors 82 periodically 120 engage in the holes of the carriers 71, 71 for ejecting therefrom the finished matches 24. Of course any other known ejecting device may be employed in place of the one just described. Beneath the hoppers 75, 75 125

passes a long slide 83, which is guided in suitable grooves of the frame 73 and has a plurality of openings that can register with the mouths of the hoppers 75, 75. The slide 83 is actuated from the cam disk 39 on the shaft 34 in the following manner. A shaft 84 is mounted in the frame to rock and has fastened on it two arms 85 and 86, of which the arm 85 is pivotally connected with the slide 83 and the other arm 86 is pivotally connected with a rod 87. The lower end of the rod 87 is forked and is guided on the shaft 34 between the cam disk 39 and the loose collar 40. It carries a roller 88, which is adapted to roll on the periphery of the cam disk.

The trough formed by the support 20 (Fig. 3) and the side plates 22 and 23 is above closed with a plate 89, which is adapted to consecutively receive the drawers 90, 90 of the match boxes from four juxtaposed magazines 91, 91 of any known construction. The two side walls of the trough 21 are each cut out on four places so as to form openings, which register with the receptacles I, II, III, IV of the carrier E at the end of the trough 21. Four parallel ejectors 92 guided horizontally in suitable supports 93 on the table 6 are adapted to simultaneously eject the matches 24, 24 from the four receptacles I, II, III, IV of the carrier E to chambers 94, in which four pistons 95 are vertically guided for raising the ejected matches and pushing them into drawers 90, 95 that have been shifted from the plate 89 by ejectors 96. On the table 6 another table 97 (see Fig. 3) is disposed, which is on a level with the plate 89 and carries four juxtaposed magazines 98 for the casings 99 of the match boxes and a pair of rolls 100, 100 for pushing the casings 99 over the filled drawers and thus closing the boxes. The rolls 100, 100 are driven from the machine in any known manner. The lowermost casings 99 in the four magazines 98 can be moved beneath the right rolls 100 by separate ejectors 101. I have illustrated the match boxing device only in its features for the purpose of facilitating the understanding of the invention, and I desire it to be expressly understood, that I do not bind myself to the construction of the match boxing device, as it forms no part of my invention.

The conveying device described operates as follows: The match carriers 71, 71 of the dipping device are intermittently fed forward in the direction of the arrow 72 in Fig. 2 and the matches 24, 24 are ejected from them one series after the other, so that they fall into the hoppers 75, 75. The cam disk 39 is so adjusted as to close by the slide 83 the mouths of the hoppers 75, 75 each time that matches are ejected from the carriers 71, 71, and to afterward open the said

mouths for permitting the matches to drop into the receptacles I, II, III, IV. During the rotation of the shaft 34 the two bars 51 and 56 are simultaneously moved outward in opposite directions, so that the left end 70 of the upper bar 51 moves into the left rotary transfer device D until its spring-pressed pawl 59 engages in the right notch 25 of the upper carrier E on the left rotary transfer device and at the same time the 75 right end of the lower bar 56 moves into the right rotary transfer device D until its spring-pressed pawl engages in the left notch 25 of the lower carrier E at the right rotary transfer device D. Then the two 80 bars 51 and 56 are simultaneously moved inward in opposite directions, so that the 85 spring-pressed pawl 59 of the upper bar 51 will push forward to the right the whole of the upper series of carriers E E extending from the outer end of the left rotary transfer device D to the end of the trough 21, that is to the inner end of the right rotary transfer device D, so that the extreme left carrier E is moved off from the left rotary 90 transfer device D and the extreme right carrier E is moved on the right rotary transfer device D. At the same time the spring-pressed pawl of the lower bar 56 will push forward to the left the whole of the lower 95 series of carriers E E extending from the outer end of the right rotary transfer device D to the end of the two angle-irons 27, 27, that is to the inner end of the left rotary transfer device D, so that the extreme 100 right carrier E is moved off the right rotary transfer device D and the extreme left carrier E is moved on the left rotary transfer device D. As the match carriers 71, 71 of the dipping device are shown to have a 105 length sufficient for simultaneously charging the receptacles I, II, III, IV, of three consecutive carriers E E, it is evident that the receptacles of each carrier E are thrice 110 filled during the path along the match carriers 71, 71. In other words, the receptacles of the first left carrier E beneath the charged match carriers 71, 71 will each contain but one charge of matches, while the receptacles of the second following carrier 115 will each contain two charges and those of the third and following carriers three charges of matches. Then the cam disk 41 will by the parts 67, 66, 64, 65 and 63 turn the shaft 15 with the two rotary transfer devices D D through an angle of 60° in the direction of the arrow 68 in Fig. 4, so that the left rotary transfer device D will move one carrier E into the line of the trough 21 and the right rotary transfer device D will 120 move its freshly received carrier E out of the said line. Thereupon the four ejectors 92 in Fig. 3 will eject the matches from the four receptacles I, II, III, IV of the carrier E beneath the four magazines 91, 91 to the 125 130

four chambers 94 and the four ejectors 96 will eject the drawers 90, which have dropped from the magazines 91, 91, from the plate 89 to the top faces of the chambers 94. Afterward the four pistons 95 will raise the matches 24 and press them into the drawers 90, whereupon the four ejectors 96 will eject the filled drawers 90 from the top face of the boxes 94 to the table 97. Here the 10 drawers 90 are held in any known manner (not shown), while the four ejectors 101 eject the lowermost casings 99 from the four magazines 98 beneath the right rolls 100 in Fig. 3, so that the latter can push the casings 99 15 over the drawers 90 and thus close the filled match boxes. From the construction described of the rotary transfer devices D D it follows, that after three revolutions of the shaft 34 the upper carrier E which has 20 been moved on the right rotary transfer device D in Fig. 1 will be brought into the line of the lower series, whereupon it can be moved off the right rotary transfer device by the spring-pressed pawl of the lower bar 25 56. After further three revolutions of the shaft 34 the extreme left carrier E, which has been moved on the left rotary transfer device D, will have been moved around by the latter and brought into the line of the 30 upper series.

It is obvious, that the length of each carrier E will be practically not altered by the wear and tear, so that the length of the whole series of carriers in the trough above 35 as well as that of the whole series of carriers below will practically remain invariable. Only the spring-pressed pawls 59 of the two bars 51 and 56 are subject to the wear and tear, but it is easy to make 40 them from the best hardened steel so that they will last for a long time, and it is further easy to readjust the links 53 and 56 from time to time in order to insure an exact working of the whole mechanism. 45 When worn off, the pawls can be exchanged for fresh ones. In this manner the exactitude of the operation of the mechanism is guaranteed for an extremely long time, so that the new conveying device is far superior to the old endless chain.

Obviously the conveying device described can also be applied to those complete match machines, in which the matches ejected from the carriers of the dipping device fall into 55 drawers of the boxes and are then at once pushed with the drawers into the casings. In this case the magazines 91, 91 shown at Fig. 1 may be left on their place, so that they are in any known manner adapted to 60 simultaneously drop the lowermost drawers 90 into the receptacles I, II, III, IV of any carrier E, the bottoms of the drawers being turned downward so that the drawers are ready to receive the matches through the 65 hoppers 75, 75 of the frame 73. The mech-

anism is so modified, that the carriers E E of the upper series are intermittently moved from right to left and those of the lower series from left to right. The table with the magazines 98 for the casings and with 70 the respective ejectors and pistons is then disposed on the left side of the left standard 1 in Fig. 1.

It depends upon the construction of the respective complete match machine and upon 75 the circumstances, how many receptacles each carrier E should comprise and at what distances from one another they are disposed.

The walls of the receptacles I, II, III, IV 80 are shown to be cast in one piece with the base of the carrier, but it is evident, that the receptacles may be made separate and exchangeable if so preferred.

The conveying device can be varied in 85 many respects without departing from my invention.

I claim:

1. In a machine of the character specified, the combination with upper and lower 90 guideways, of article feeding mechanism adapted to discharge over one of said guideways and having a plurality of discharge openings, a series of independent juxtaposed article carriers normally resting motionless 95 in each of said guideways, a rotary transfer device arranged in proximity to the ends of each guideway, independent means acting respectively on one end carrier in each guideway for moving the entire series of carriers 100 as a unit and advancing the carrier opposite the end acted upon by said means into the adjacent transfer device, means for simultaneously disclosing the discharge openings in the feeding mechanism whereby a pre-determined quantity of articles is simultaneously fed to all the carriers in line with the feeding mechanism, and means for rotating said transfer devices whereby said carriers are successively transferred from 110 one guideway to the other.

2. In a machine of the character specified, the combination with upper and lower guideways, of article feeding mechanism adapted to discharge over one of said guideways, a series of independent juxtaposed article carriers normally resting motionless 115 in each of said guideways, each of said carriers being adapted to receive and retain a plurality of separated charges of articles, a 120 rotary transfer device arranged in proximity to the ends of each guideway, independent means acting simultaneously on one carrier in each series to advance both series as a whole and force one carrier of each 125 series into one of the rotary transfer devices, means whereby said feeding mechanism discharges a predetermined quantity of articles into all the carriers in line therewith after each advance of said series, and means for 130

rotating said transfer devices whereby said carriers are successively transferred from one guideway to the other.

3. In a machine of the character specified, 5 the combination with upper and lower guideways, each being provided with a slot through one wall thereof, of a series of article carriers adapted to be moved in said guideways, each article carrier having 10 opposed notches in one of its walls, and means adapted to pass through the slots in the guideway and into the notches in the carriers for moving the latter in the guideways.

15 4. In a machine of the character specified, the combination with an upper and lower guideway, each thereof having a slot formed therein, a series of article carriers adapted to be moved in said guideways, each said 20 carrier having its lower face provided with a pair of opposed notches, and means for advancing the carriers in the guideways, said means comprising a reciprocable bar having a spring pressed pawl adapted to 25 pass through the slot in the guideway and engage one of the notches in the carrier.

5. In a machine of the character specified, the combination with an upper and a lower guideway, each thereof having a slotted 30 wall, of article feeding mechanism adapted to discharge over the upper guideway a series of article carriers movable in the guideways, and each article carrier having its lower wall provided with opposed notches, means 35 for advancing said carriers in the guideways, said means comprising a reciprocable bar having a pawl adapted to engage one of the notches in one of the carriers when said rod is in a predetermined position, and means 40 whereby said article feeding mechanism is caused to discharge predetermined quantities of articles in the article carriers in the upper guideway.

6. In a machine of the character specified, 45 the combination with an upper and a lower guideway, of a series of article carriers adapted to be advanced in said guideways, each said article carrier having a pair of opposed notches in its lower wall, article 50 feeding mechanism adapted to discharge predetermined quantities of articles into the carriers in the upper guideways, means for advancing the article carriers in the guideways, said means comprising a reciprocable 55 bar carrying a normally inactive pawl which is adapted to become active and engage one of the notches in one of the carriers, and a rotary transfer device at the ends of each guideway whereby the said carriers are 60 adapted to be transferred from one guideway to the other.

7. In a machine of the character specified, the combination with upper and lower oppositely directed guideways, the opposed 65 walls of the respective guideways being

partially slotted, of a series of article carriers movable in each guideway, each said article carrier having a pair of opposed notches in its lower face, a reciprocable bar slidable along the slotted wall of each guideway, a 70 pawl carried by each bar and being in inoperative position until said pawl is in line with the slot in the guideway, means for reciprocating said bars to advance the article carriers in the guideways, and rotary 75 transfer devices whereby the article carriers are transferred from one guideway to another.

8. In a machine of the character specified, the combination with the machine frame and driving shaft journaled therein, of upper and lower guideways carried by the machine frame, a series of article carriers adapted to be advanced in said guideways, each said article carrier having a pair of opposed 80 notches on its under face, a reciprocable bar having a spring pressed cam for entering said notches and advancing the article carriers in each guideway, cams carried by the driving shaft for reciprocating said bars, a 90 second shaft arranged intermediate the pair of guideways, rotary transfer devices carried at the extremities of said second shaft, and means on the main shaft for revolving said second shaft with its rotary transfer 95 devices, whereby the article carriers are transferred from one guideway to the other.

9. In a conveying device for match-machines, the combination with a frame, of a horizontal shaft mounted in said frame to 100 turn, two troughs secured in said frame above and below said shaft, two rotary transfer devices fastened at the ends of said shaft in proximity to the ends of said two troughs, carriers of like length and shape 10 and each comprising a plurality of receptacles open on the sides, each carrier having on the sides of its base grooves and on the underside two notches and being adapted to slide in said two troughs, each of said two troughs being adapted to contain an even number of said carriers, each of said two rotary transfer devices having a plurality of parallel pairs of opposite ribs which are adapted to periodically come into the line of 110 either of said two troughs and to engage in the grooves of any said carriers, two bars guided in said frame beneath the upper trough and above the lower trough, the upper bar being provided at one end with a 120 spring-pressed pawl for engaging in one notch of any carrier and adapted to engage with this end in one rotary transfer device and the lower bar being provided at the opposite end with a spring-pressed pawl for 125 engaging in the other notch of any carrier and adapted to engage with this end in the other rotary transfer device, a ratchet wheel fastened on said shaft, a lever rocking on said shaft and carrying a pawl adapted to 130

engage said ratchet wheel, a cam shaft mounted in said frame to turn and adapted to be driven from the machine, a cam disk fastened on said cam shaft and adapted to actuate said lever, two cam drums with oppositely disposed cam grooves fastened on said cam shaft, and means operated from

the cam grooves of said two cam drums for simultaneously reciprocating said two bars in opposite directions.

OTTO H. LANDVATTER.
